UNITED STATES PATENT OFFICE.

CHARLES A. BRIGGS, OF CHINO, CALIFORNIA.

BINDER FOR CARDS AND THE LIKE.

Application filed May 26, 1925. Serial No. 33,010.

To all whom it may concern:

Be it known that I, CHARLES A. BRIGGS, a citizen of the United States, and a resident of Chino, in the county of San Bernardino and State of California, have invented 5 a new and useful Improvement in a Binder for Cards and the like, of which the following is a specification.

The present invention relates generally 10 to binders for cards, leaves and the like, and has specific reference to binders wherein the titles, names or the like appearing in the marginal portions of the leaves or cards are visible as an index.

15 The general object of the invention is to provide for the detachable binding of one or more series of alphabetically arranged cards or leaves within a casing such as a book cover, file or the like, so that each 20 series may be turned independently of the others as the leaf of a book and, additionally, to provide automatically for the prevention of a break or gap between any two adjacent leaves or cards of a series upon the 25 removal of an intervening card, and further to permit the introduction of a new card or leaf into any section of a series so as to occupy the same relative position as the other cards or leaves therein, and this without disturbing the relative positions of the 30 other cards or leaves.

The above and other objects are accomplished by instrumentalities pointed out in the following specification.

35 The invention is clearly defined in the claims.

A satisfactory embodiment of the invention is illustrated in the accompanying drawings forming part of the specification 40 and in which

Figure 1 is a plan view.

Figure 2 is a vertical cross-section on the line 1—1 of Figure 1.

45 Figure 3 is a view similar to Figure 1, showing the movable plate adjusted to a different position.

In the embodiment shown 5 is the base plate of metal or any other suitable material which, when the device is in use, will 50 be permanently attached to a convenient part of a casing. If such casing be a book, the base 5 will be permanently attached to the intervening section between the movable covers and will be similarly and conveniently attached to desirable portions of other forms of casings if these are used. 6 is a

plate superimposed on base plate 5 and immovable therewith. 7 is a plate corresponding to plate 6 and arranged alongside thereof. Both plates are preferably of metal 60 and the plate 7 is also superimposed upon base plate 5. Plate 7 is movable within the confines of pin and slot connections, the pins 8 of which are herein shown as extending outwardly from the opposite end portions 65 of base plate 5 and passing through similarly disposed angular shaped slots 9 in plate 7. As shown each side of each of the slots 9 extends outwardly from approximately the middle longitudinal line of plate 70 7 so that when said plate 7 is positioned as shown, the outer sides of the slots will function as cams and by reason of their angular contour plate 7 will move longitudinally and laterally outward for a distance and then longitudinally and laterally inward in the act of moving the plate for the length of either slot. The plate 6 carries a series of spaced semi-circular shaped prongs 10, the inner ends of which are suitably secured to the plate as by being riveted thereto. A series of mating or companion prongs 11 is carried by plate 7 and conform in contour to the prongs 10 and are secured to the plate 7 in a similar manner. As will be 75 noted, the prongs of each series are arranged in spaced relation and the spacing between any two adjacent prongs corresponds to the distance between the ends of slots 9. The prongs 10 and 11 are also constructed and 80 arranged so that they will register and form continuations one of the other when the plate 7 is at either end of the movement afforded by the pins 8, and it may be further stated that the spacing between any 85 two adjacent prongs in each series further corresponds to the width of the usual margin required for each leaf or card in the conventional types of indexed binders.

In operation the cards or leaves which, in 100 width of course, are appreciably less than the length of either series of prongs, are arranged consecutively in alphabetical order. A series of such leaves or cards corresponding in length to the leaf of a book is had by 105 arranging the uppermost card so that the several openings in the side thereof engage with the uppermost of those of the succeeding prongs 10 for which openings in the uppermost card are provided. The second 110 card is then engaged with the second and succeeding prongs 10 and so on until the last

card of the series extends to the opposite end of the casing. When the cards are so positioned the series may be moved as the leaf of a book by engaging the uppermost card 5 from underneath and turning the same to the left and a similar result will be had in turning the series in the opposite direction by engaging the lower card or leaf. When it is desired to remove any particular card 10 with the parts as shown by full lines in Figure 1, plate 7 is moved longitudinally until a gap or space is presented between the opposite series of prongs. In this position of the parts the prongs of one series will be 15 offset with respect to the prongs of the other series and laterally spaced for a distance corresponding to the width of any of the slots. The lower card, for instance, may now be conveniently removed by turning 20 the same to a vertical position and until it enters the space between the prongs after which it may be readily lifted, and the parts restored to their original positions by sliding plate 7. In the operation of removing 25 one of the intermediate cards, the cards superimposed upon the one to be removed are turned over and upon the prongs 11, after which plate 7 is moved to provide for the space as previously described. The near- 30 est wholly exposed card or the one to be removed is then turned and lifted through the space between the prongs. Now it will be obvious that if plate 7 were restored to its original position by a return movement and 35 the cards held by the prongs thereof turned to their original positions, a gap or space would exist in the place left vacant by the removed card. With the present invention, however, the presence of such gap or space 40 will be prevented by causing a continuation of the longitudinal movement of plate 7 until the space between the prongs is closed at which time those of the prongs 10 then in registry with the prongs 11 will be those 45 successively disposed to the prongs previously in registry so that when the several cards are returned from the prongs 11, their relative positions will be advanced toward one end of the series for a distance cor- 50 responding to the spacing between adjacent prongs. This will have the effect of maintaining the several cards of the series in the same relative positions had before the removal of the aforesaid card. 55 Although I have shown and described one embodiment of my invention, it is to be

understood that the same is susceptible of various changes; and I reserve the right to employ such as may come within the scope of the appended claims. 60

I claim:

1. In a temporary binder two plates arranged one adjacent to the other and each provided with a plurality of prongs, said prongs being arranged in adjacent spaced relation on said plates and normally registering, one of said plates being adapted to move longitudinally and laterally outward with respect to the other of said plates to provide a lateral separation of the prongs 70 and then move longitudinally in the same direction and laterally inward to register the prongs thereof with successively disposed prongs on the other plate, said plates being provided with means for guiding the 75 movable plate in its movements.

2. In a temporary binder, a base plate, two plates arranged one adjacent to the other and superimposed on the base plate 80 and each provided with a plurality of prongs arranged adjacent to one another and in spaced relation on said plates and normally registering, one of said superimposed plates being adapted to move longitudinally and laterally outward with respect to the other 85 plate to provide a lateral separation of the prongs, and then longitudinally in the same direction and laterally inward to register the prongs thereof with successively disposed prongs on the other plate, said base and 90 movable plates being provided with means for guiding the movable plate in its movements.

3. In a temporary binder, a base plate, two plates arranged one adjacent to the 95 other and superimposed on the base plate and each provided with a plurality of prongs arranged adjacent to one another and in spaced relation on said plates and normally registering, one of said superimposed plates being adapted to move longitudinally and laterally outward with respect to the other plate to provide a lateral separation of the prongs, and then longitudinally in the same direction and laterally 100 inward to register the prongs thereof with successively disposed prongs on the other plate, said base and movable plates being provided with pin and slot connections for 105 guiding the movable plate in its movements.

CHARLES A. BRIGGS.
